WALL PLATE

Louis Blum and William J. Horgan, Jr., Pittsburgh, Pa., assignors to Blumcraft of Pittsburgh, Pittsburgh, Pa., a firm consisting of Hyman Blum, Louis Blum, Max
Blum, and Harry P. Blum

Filed Dec. 13, 1963, Ser. No. 77,781

Term of patent 14 years

(Cl. D13—7)

FIG. 1.

FIG. 2.

FIG. 3.

FIG. 1 is a perspective view showing the front of a wall plate embodying our new design with a railing mounting bracket connected thereto shown in broken lines;

FIG. 2 is a perspective view from the opposite side of the wall bracket shown in FIG. 1;

FIG. 3 is a cross-sectional view through the wall bracket of FIGS. 1 and 2.

The broken line showing of a bracket in FIGURES 1 and 2 is for illustrative purposes only.

We claim:

The ornamental design for a wall plate, as shown and described.
